[57] CLAIM

The ornamental design for a foldable tray for puzzle or the like, as shown and described.

DESCRIPTION

FIG. 1 is a top plan view of a foldable tray for puzzle or the like showing my new design;

FIG. 2 is a bottom plan view thereof;

FIG. 3 is a rear elevation view thereof;

FIG. 4 is a front elevation thereof;

FIG. 5 is a left side elevation thereof;

FIG. 6 is a right side elevation thereof;

FIG. 7 is a perspective view thereof; showing assembly of parts for clarity of illustration; and

FIG. 8 is a perspective view of the board thereof; in folded position.

FIG. 1

FIG. 2

FIG. 3

FIG. 4

FIG. 5

FIG. 6

FIG. 7

FIG. 8
